UNITED STATES PATENT OFFICE.

CHARLES H. HAZELTON, OF LAKewood, OHIO, ASSIGNOR TO NATIONAL CARBON COMPANY, INC., A CORPORATION OF NEW YORK.

ELECTRODE-ADAPTER.

1,330,532.

Specification of Letters Patent. Patented Feb. 10, 1920.

Application filed September 9, 1918. Serial No. 253,132.

To all whom it may concern:

Be it known that I, CHARLES H. HAZELTON, a citizen of the United States, residing at Lakewood, in the county of Cuyahoga and State of Ohio, have invented a certain new and useful Improvement in Electrode-Adapters, of which the following is a full, clear, and exact description.

This invention relates to adapters or holders for electrodes of electric arc lamps. The improvement is particularly applicable to projection apparatus for motion pictures.

It is customary for this service to use projection apparatus which is suited for various conditions. For instance, the machines usually are adapted for either alternating or direct current. With alternating current the positive and negative electrodes preferably are the same size, but with direct current a negative of considerably smaller diameter than the positive is used. In either case prior holders are adapted to have bushings fitted therein to take various sizes of electrodes. With this type of projector adapted for various kinds of service, the electrode-feeding mechanism only permits the holders to approach each other until the distance between them is about five inches. Consequently at least a two and one half inch stub of each electrode must be thrown away.

With direct current projector arc lamps using a small metal coated negative, it would be permissible to burn the electrode to a much shorter stub as the arc flame is directed away from the holder of the negative, and my invention relates to an adapter for the negative electrode which will permit this without changing the lamp adjustment.

The structure of the adapter will be set forth in the following description and illustrated by the drawings in which:

Figure 1 is a longitudinal cross section of the adapter with a short electrode stub clamped therein.

Fig. 2 is a side view.

Fig. 3 is a plan view.

Figs. 4 and 5 are end views from the right and left hand sides respectively of Fig. 1.

Figs. 6 and 7 are pseudo perspective views of a detail, the former being upright and the latter inverted.

The body of the adapter preferably is made from a copper casting because the copper in addition to being a good electrical con-

ductor also withstands the heat and the corrosive influences within the arc chamber. The major portion of the length of the casting is in the form of a tube 1 of such diameter that the end may be readily fastened in the negative electrode holder of the projection apparatus in place of the electrode or the bushing which is ordinarily fitted therein. The inner diameter of the tube is only slightly less than the outer diameter so that the ordinary sizes of negative electrodes may be passed therethrough. The clamping end consists of an enlarged hollow head 2 integral with the tube. The lower portion 3 of the enlarged head extends almost in a straight line with the lower surface of the tube 1 and has a trough shaped groove 4 adapted to receive various sizes of electrodes. A hole 5 is also cast in this surface for a purpose to be referred to later.

The upper portion 6 is offset from the tube and connected to the bottom 3 by parallel sides 7 which serve as guides for a small movable clamping block 8 for the electrode. A threaded hole 10 is cut in the center of the upper portion 6 and directly below the hole 10 a hole 11 is provided in clamping block 8. A threaded rod 12 having a wing nut 13 is fitted in threaded hole 10 and provided with a projection 14 of smaller diameter than the threaded portion 12. The shoulder at the end of the threaded portion abuts against the top of block 8 and the projection fits in hole 11. The block is fastened to the end of the rod by burring or riveting the end, which operation is conveniently accomplished by passing the riveting tool through the lower hole 5 provided for this purpose. The adjustable block is thus permanently fastened to the clamping screw in an inexpensive, durable manner, and no machining of any of the parts is necessary.

When a new electrode is put in the machine it will pass through the tube and be clamped in the desired position by turning the screw 12 until the electrode is clamped between the block 8 and the bottom of the head. The use of a special bushing for various sizes of negative is therefore eliminated and the adapter thus saves the expense and inconvenience of providing bushings. As the electrode is consumed it is moved forward in the clamp and may be used until the stub is only $\frac{1}{2}$ inch to 1 inch long, as

shown in Fig. 1 of the drawings. The length of the electrode saved is about the same as the length of the adapter.

An improved result obtained by the use 5 of the grooved clamping surfaces is the elimination of breakage. The electrode is clamped along several longitudinal lines or surfaces instead of at a single point.

In projection apparatus the positive electrode is of large diameter and emits a flame which makes it impractical to burn it very short, and in alternating current lamps it is impractical to burn the electrodes to very short stubs, but obviously my improvement 10 can be used for such purposes if desired, and need not be limited to use with negative electrodes.

Having described my invention, what I claim, is:

- 20 1. In adapters for arc lamp electrodes, a metal tube adapted to be clamped at one end in an electrode holder to electrically connect the tube with the holder, said tube having a passage therethrough for an electrode, a block movably mounted in the other end of the tube and a set screw passing through the tube and engaging the block.
- 25 2. In adapters for arc lamp electrodes, a metal tube adapted to be clamped at one end in an electrode holder to electrically connect the tube with the holder, said tube having a passage therethrough for an electrode, a guide attached to the other end of the tube, a clamping block movably mounted in the 30 guide, and a set screw passing through the 35 guide and engaging the block.

3. In adapters for arc lamp electrodes, a tube adapted to be clamped at one end in an electrode holder and having a passage therethrough for an electrode, an enlarged 40 guide head integral with the tube at the other end of the tube and having a hole, a clamping block movably mounted in the guide head, and a set screw passing through the hole and engaging the clamping block. 45

4. In adapters for arc lamp electrodes, a tube adapted to be clamped at one end in an electrode holder and having a passage therethrough for an electrode, an enlarged 50 guide head integral with the tube at the other end of the tube and having a threaded hole and a grooved bottom opposite said hole, a clamping block movably mounted in the guide head and adapted to coöperate with the grooved bottom to hold an electrode, and a set screw fitted in the hole and engaging the clamping block. 55

5. In adapters for arc lamp electrodes, a tube adapted to be clamped at one end in an electrode holder and having a passage therethrough for an electrode, an enlarged 60 guide head integral with the tube at the other end and having a pair of holes therein opposite to each other, a grooved clamping block slidably mounted in the guide head, and a set 65 screw fitted in one hole of the guide head and having one end fitted in the clamping block and riveted at a point opposite the other hole in the guide head.

In testimony whereof I hereunto affix my 70 signature.

CHAS. H. HAZELTON.
